METALLIC CONTAINER

Wallace C. Mills, Rockford, Ill., assignor to J. L. Clark Manufacturing Co., Rockford, Ill., a corporation of Illinois

Application November 12, 1934, Serial No. 752,618

12 Claims. (Cl. 220—10)

The invention pertains to small jars of the type employed as containers for cold cream ointments and the like. Containers of this class are commonly made of glass and therefore subject to the objection that they are relatively heavy and susceptible of breakage, so that shipping costs are high and there is danger of injury to the user.

The primary object of my invention is to provide a jar or container of the character indicated embodying a novel and advantageous sheet metal construction, such that the advantages of a glass container are retained without its accompanying disadvantages.

Another object is to provide a jar or container of the character set forth constructed of sheet metal in a manner such as to provide a smooth interior surface having no joints or crevices and an outer surface free from rough and sharp edges.

The objects of the invention thus generally stated together with other and ancillary advantages are attained by the construction and arrangement illustrated in the accompanying drawing forming a part hereof wherein:

Figure 1 is a perspective view of a sheet metal container constructed in accordance with my invention.

Fig. 2 is a central vertical sectional view through the container as shown in Fig. 1.

Fig. 3 is a similar view but showing a modified construction.

In carrying out my invention, I employ a double walled construction for the container comprising inner and outer shells spaced apart to form a narrow annular air space between them and having their upper end portions coacting to form a neck of reduced diameter adapted to receive the skirt of a closure cap. The two shells are moreover constructed to provide an entirely smooth interior surface, with the upper end of the neck portion in the form of a broad rounded edge and with the exterior of the container entirely free of rough and sharp edges.

Referring now to Figs. 1 and 2 of the drawing, a preferred embodiment of the invention comprises spaced inner and outer shells 7 and 8 having their upper end portions coacting to form a neck 9 of reduced diameter. 10 designates a closure cap having a depending skirt 11 fitting over the neck 9.

To provide an interior surface entirely free from joints or crevices, I form the inner shell 7 from a single sheet of metal drawn to provide a bottom wall 9^a and a peripheral side wall 10^a, which latter is preferably of uniform diameter

from top to bottom. The outer shell 8 comprises a vertical peripheral side wall 12 and a bottom wall 13. The side wall is made from relatively light gauge sheet metal, and has its lower edge portion terminating in an inward and upward curl 14. The bottom wall 13, which may be made of metal or other suitable material, is in the form of a disk resting near its peripheral edge upon the upper edge of the curled portion 14 of the outer shell. As shown in Fig. 2, the bottom 9^a of the inner shell rests upon the disk 13 which is thus interposed between the curl 14 and the bottom 9 of the inner shell. Thus the latter is in effect supported against downward movement by the curl 14.

Between the two peripheral side walls 10^a and 12 is formed an annular insulating air space 15 which is closed at its lower end by the peripheral portion of the bottom wall 13 of the outer shell. As shown in Fig. 3, the bottom wall of the outer shell may be omitted, in which event, the inwardly and upwardly curled flange 14' may engage directly with the bottom wall 9^a of the inner shell and serve to support the latter directly as well as to close the lower end of the annular space 15.

The neck 9 is preferably formed to provide a broad rounded upward edge 9^b for the container, and in securing the two sheets together at the upper end of the container, I employ a construction such as to avoid exposed sharp or rough edges. Accordingly, the upper end of the inner shell has formed integral therewith a wide flange which is bent outwardly and downwardly to provide an annular collar 16 of substantial width forming the outer surface of the neck 9; and I provide at the upper end of the outer shell 12 a flange 17 which is folded inwardly and downwardly in snugly fitting engagement with the lower end portion of the collar 16. Preferably, the latter is spaced outwardly from the peripheral wall of the inner shell to form within the neck portion an upward extension of the annular space 15. By the use of an inwardly bent or folded flange 17, the upper free edge of the outer side wall 12 is effectually concealed and at the same time, an upwardly facing smooth shoulder 18 is formed at the lower end of the neck 9.

While the tightly fitting engagement between the inturned flange 17 and the lower end of the collar 16 is such as to produce a binding frictional contact between the parts, preferably the extreme lower end of the collar is bent or flared outwardly to form a radial abutment 16^a engaging with the lower inturned edge of the flange 55

17. Thus, movement of the inner shell upwardly with respect to the outer shell is positively prevented, while relative downward movement is prevented by the inturned curl or flange 14 at the bottom of the outer shell acting through the disk 13, in Fig. 2, or directly in Fig. 3, with the bottom of the inner shell.

18. The cap 10 is preferably formed with a bowed top 19 with which the skirt 11 is formed integral. 10 Within the cap may be fitted a liner of any suitable material in the form of a flat disk 20 forming between it and the bowed top 19 an air space 21. The lower free edge of the skirt 11 is preferably formed with an inwardly and upwardly folded 15 flange 22 forming a smooth rounded edge for the skirt and terminating adjacent the shoulder 18. By this arrangement, the skirt 11 of the cap is disposed substantially in the plane of the peripheral side wall 12 of the outer shell.

20. If desired, the cap may be fastened onto the body of the container by interengaging screw threads. Thus as shown in Fig. 3, the peripheral skirt 11 of the cap may be formed with protruding threads 23, and corresponding outwardly protruding threads 24 formed on the collar 16. I have also shown in Fig. 3, the upper edge of the outer peripheral side wall 12 terminating in a rounded inwardly projecting bead 17, as distinguished from the flat fold employed in the construction shown in Fig. 2.

25. It will be observed that I have provided a container of the class set forth, which is of a very practical character. Thus, notwithstanding the sheet metal construction employed, an entirely 30 smooth interior surface is provided. Also, the outer surface is free from rough and sharp edges. Accordingly, in the use of the container, all possibility of injury to the fingers is effectually eliminated. Moreover, the container is advantageous 35 as compared to those made of glass in that it is light in weight, which is a material advantage in the case of foreign shipments, and is not subject to breakage either in shipment or in use. The sheet metal construction furthermore lends itself 40 readily to attractive decoration in that the metallic surfaces may be readily lithographed. Finally, because of the construction employed, the container presents a neat and attractive appearance.

45. I claim as my invention:

50. 1. A container of the class set forth comprising inner and outer shells having peripheral side walls spaced apart to form a narrow annular air space between them, said inner shell having a wide flange formed integral with the upper end 55 of its peripheral side wall and bent outwardly and downwardly to form an annular collar of substantial width and providing a neck for the container having a broad rounded upper end, said outer wall having an inwardly bent upper edge portion 60 engaging snugly with the lower end of said collar and forming an upwardly facing annular shoulder at the outer side of the collar, and means at the lower end of the outer shell supporting the inner shell against downward 65 movement relative to the outer wall and closing said annular air space.

70. 2. A container of the class set forth comprising inner and outer shells having peripheral side walls spaced apart to form a narrow annular air space between them, said inner shell having a wide flange formed integral with the upper end 75 of its peripheral side wall and bent outwardly and downwardly to form an annular collar of substantial width and providing a neck for the container having a broad rounded upper end, said

outer wall having an inwardly bent upper edge portion engaging snugly with the lower end of said collar and forming an upwardly facing annular shoulder at the outer side of the collar, and said collar having an outwardly projecting abutment formed at its lower edge adapted to engage with the inturned edge portion of the peripheral side wall of the outer shell, means at the lower end of the outer shell supporting the inner shell against downward movement relative to the outer 10 wall and closing said annular air space, and a cap having a top wall and a peripheral skirt fitting over said collar and terminating adjacent said shoulder with said skirt disposed substantially in the plane of the outer side wall. 15

3. A container of the class set forth comprising inner and outer shells having peripheral side walls spaced apart to form a narrow annular air space between them, said inner shell having a wide flange formed integral with the upper end 20 of its peripheral side wall and bent outwardly and downwardly to form an annular collar of substantial width and providing a neck for the container having a broad rounded upper end, said outer wall having an inwardly bent upper edge 25 portion engaging snugly with the lower end of said collar and forming an upwardly facing annular shoulder at the outer side of the collar, and a cap having a top wall and a peripheral skirt fitting over said collar and terminating adjacent 30 said shoulder.

4. A container of the class set forth comprising inner and outer shells having peripheral side walls spaced apart to form a narrow annular air space between them, said inner shell having a wide flange formed integral with the upper end 35 of its peripheral side wall and bent outwardly and downwardly to form an annular collar of substantial width and providing a neck for the container having a smooth upper end, said outer wall 40 having an upper edge portion engaging snugly with the lower end of said collar and forming an upwardly facing annular shoulder at the outer side of the collar, and a cap having a top wall and a peripheral skirt fitting over said collar. 45

5. A container of the class set forth comprising inner and outer shells having peripheral side walls spaced apart to form a narrow annular space between them, said inner shell having a wide flange formed integral with the upper end 50 of its peripheral side wall and bent outwardly and downwardly to form an annular collar of substantial width and providing a neck for the container having a smooth upper end, said outer shell having an inturned upper edge portion fitting snugly about the lower end of said collar and forming an upwardly facing shoulder, and a cap having a depending skirt fitting over said neck and having an inturned lower edge portion terminating adjacent said shoulder. 60

6. A container of the class set forth comprising inner and outer shells having peripheral side walls spaced apart to form an annular narrow space between them, said inner shell having a wide flange formed integral with the upper end 65 of its peripheral side wall and bent outwardly and downwardly to form an annular collar of substantial width and providing a neck for the container having a smooth upper end, said outer 70 shell having an inwardly folded upper edge portion fitting snugly about the lower end of said collar, and a cap having a depending skirt with an inwardly folded lower edge portion fitting over said neck with the skirt of the cap disposed sub- 75

stantially in the plane of said outer peripheral side wall.

7. A container of the class set forth comprising inner and outer shells having peripheral side walls spaced apart, said inner shell having a wide flange formed integral with the upper end of its peripheral side wall and bent outwardly and then downwardly to form a hollow neck for the container, said outer shell having an upper edge portion fitting snugly about the lower end of said neck, and a cap having a depending skirt fitting over said neck and disposed substantially in the plane of said outer peripheral side wall.

8. A container of the class set forth comprising inner and outer shells having peripheral side walls spaced apart to form an annular narrow space between them, said inner shell having a wide flange formed integral with the upper end of its peripheral side wall and bent outwardly and downwardly to form an annular collar of substantial width and providing a neck for the container having a smooth upper end and an outwardly bent lower edge, said outer shell having a portion engaging said bent lower edge of the neck to hold the inner shell against upward movement relative to the outer shell, and an inturned flange at the lower edge of the outer side wall acting to support the inner shell against downward movement relative to the outer shell.

9. A container of the class set forth comprising an inner shell formed from a flat sheet of metal to provide a bottom wall and a peripheral side wall, a wide flange formed integral with the upper end of said side wall and bent outwardly and downwardly to form an annular collar in spaced relation to said side wall, and an outer shell having a peripheral side wall spaced from the side wall of the inner shell and engaging with the lower edge portion of said collar at the outer side of the latter, said outer shell being formed separately from the inner shell and having means at its lower end for supporting the inner shell

against downward movement relative to the outer shell.

10. A container of the class set forth comprising an inner shell formed from a flat sheet of metal to provide a bottom wall and a peripheral side wall, a wide flange formed integral with the upper end of said side wall and bent outwardly and downwardly to form an annular collar in spaced relation to said side wall, and an outer shell having a peripheral side wall spaced from the side wall of the inner shell and coacting with the lower edge portion of said collar at the outer side of the latter to form an upwardly facing shoulder, the outer shell being formed from a separate sheet of metal and having an upper end portion bent inwardly into interfitting engagement with the collar to form a smooth upper face for said shoulder.

11. A container of the class set forth comprising an inner shell formed from a flat sheet of metal to provide a bottom wall and a peripheral side wall, a wide flange formed integral with the upper end of said side wall and bent outwardly and downwardly to form an annular collar in spaced relation to said side wall, and an outer shell having a peripheral side wall with its upper end portion bent inwardly into abutting relation to the lower edge of said collar at the outer side of the latter, said collar having an outwardly bent portion for engagement by the inwardly bent upper portion of the outer shell, and means interposed between the two shells at the lower ends thereof to hold the inner shell against downward movement relative to the outer shell.

12. A container of the class set forth, having a hollow peripheral side wall formed from two sheets of metal having interengaging circumferential portions coacting to form a neck of reduced diameter having an annular upwardly facing external shoulder at its lower end, the edges of said portions terminating within said hollow side wall.

WALLACE C. MILLS.
